Primary Examiner — Ricky Pham

(57) **CLAIM**

The ornamental design for a set of fork, spoon and knife, as shown and described.

DESCRIPTION

FIG. 1 is a front perspective view of a fork in a set of fork, spoon and knife, shown separately for ease and completeness of illustration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of a spoon in a set of fork, spoon and knife, shown separately for ease and completeness of illustration;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a front perspective view of a knife in a set of fork, spoon and knife, shown separately for ease and completeness of illustration;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view.
